Primary Examiner — Natasha Vujcic*Assistant Examiner* — Gilbert B Ford(74) *Attorney, Agent, or Firm* — Pearne & Gordon LLP(57) **CLAIM**

The ornamental design for a back support, as shown and described.

DESCRIPTION

FIG. 1 is a rear view of a first back support showing my new design;

FIG. 2 right side view thereof;

FIG. 3 is a front right perspective view thereof;

FIG. 4 is a front view of thereof;

FIG. 5 is a front left perspective view thereof;

FIG. 6 left side view thereof;

FIG. 7 is a rear view of a second back support showing my new design;

FIG. 8 right side view thereof;

FIG. 9 is a front right perspective view thereof;

FIG. 10 is a front view of thereof;

FIG. 11 is a front left perspective view thereof; and,

FIG. 12 left side view thereof.

The broken lines in the figures showing a human form are for the purpose of depicting environment and form no part of the claim. The cross hatching utilized in the drawings indicates a contrasting appearance.

1 Claim, 12 Drawing Sheets(56)
